UNITED STATES PATENT OFFICE.

HARRY L. HAWKINS, OF PHILADELPHIA, PENNSYLVANIA, ASSIGNOR TO WALTER S. MAYER, OF PHILADELPHIA, PENNSYLVANIA.

ELECTRIC CONDUCTOR SUPPORT.

Application filed August 8, 1921. Serial No. 490,593.

To all whom it may concern:

Be it known that I, HARRY L. HAWKINS, a citizen of the United States, residing at Philadelphia, in the county of Philadelphia, 5 and State of Pennsylvania, have invented an Improved Electric Conductor Support, of which the following is a specification.

My invention relates to electric conductor supports adapted to be applied to the tops 10 of poles or the like, and its primary objects are to provide an improved device of simple, strong and efficient construction that can be produced at relatively small cost and can be applied with facility, with avoidance of defects common to prior constructions.

Heretofore devices of this character have required special forging of the main supporting member or members, the cutting of 20 the pole to fit the parts of the device thereto, the boring of numerous holes in the pole proper, the use of parts of such bulk as to be objectionable in shipping, and the use of a pole with its top substantially flush with the top of the supporting device.

The improvements of my device are such 25 that only two bolts are necessary for securing it to the pole, no forgings are required, the parts can be knocked down in compact form for shipping, and the finished construction 30 is rigid, lends itself to corner turning and has the requisite design for resisting the stresses in various directions to which it is subjected. The device combines maximum strength with minimum weight, provides for 35 incorrect drilling of the pole, and avoids the necessity for cutting the pole to fit the structure thereto. The means to which the wire or conductor fittings are attached bear such relation thereto that should a wire or conductor break, short circuit cannot occur due 40 to its fall. The device supplements the length of the pole, thus permitting the use of shorter poles and reducing the cost per pole for a given clearance.

The improvements of my invention will be 45 fully understood from the following description and the accompanying drawings setting out an embodiment of the same.

In the drawings, Fig. 1 is an elevation of 50 a support embodying my invention attached to a pole in the operative position; Fig. 2 is a plan view of the same; and Fig. 3 is a top view of the upright angle bar on the line 3^x-3^x of Fig. 1.

The support, in the form thereof here se-

lected for the purpose of illustrating the invention, comprises the angle iron cross arm or beam 1, which is preferably straight, and to which is detachably connected the upright angle iron member or strut 2, by means of the flat iron gusset 3, the latter connected to a leg thereof by the bolts or rivets 3' and to the transverse parallel leg of the member 1 by the bolts 3''. The top of the angle bar 2 has its upper end cut off at right angles to its length and the projecting free end of the complementary leg bent at right angles in bearing relation therewith, to provide a bearing 2' in which is formed a bolt hole 2''. The parallel vertical legs 1 and 2 are 60 fixed to the top of the pole 4 by the respective bolts 5 and 6, the former passing through the gusset 3 and the latter through a longitudinal slot 2''' in the web engaging the post to avoid the necessity for accuracy 65 in spacing the two holes bored in the post for making the connections. The slot 2''' can be formed at the desired distance below the top of the member 2 for extending the latter the desired distance above the top of 70 the pole and supplementing the length thereof.

A yoke 7 of strap iron has its median section fixed to the pole 4, on the opposite side thereof from the member 1, by the bolt 5 85 which passes therethrough. The yoke 7 is bent to the form of a symmetrical bow and has its ends fixed to the respective ends of the member 1 by the bolts 8 passing the vertical legs of such member.

The cross arm 1 has symmetrically positioned on its horizontal web the insulators 9, secured by the bolts 10, and the vertical member 2 has the insulator 11 secured on the bearing 2' by the bolt 12, the arrangement 90 distributing the load from the wires symmetrically.

As the members 1, 2 and 3 lie in a plane they can be attached to the pole readily without fitting or cutting, can be handled or 100 shipped readily in assembled relation, or can be shipped in dissociated relation and readily assembled. The strap 7 can be shipped in its straight form and readily sprung to shape to place it in its assembled 105 relation, where it combines with the member 1 to form a truss adapted for resisting the stresses to which it may be subjected by forces acting in various directions. The member 2 has the advantage of carrying its 110

normal vertical load by longitudinal compression therein and the angularly disposed webs provide desired resistance to lateral stresses.

5. Having described my invention, I claim:—

1. In an electric conductor support, the combination with a cross arm, of an insulator support comprising a strut fixed in transverse relation to and projecting above 10 said arm, and a yoke having its ends fixed to said arm on opposite sides of said strut.

2. In an electric conductor support, the combination with a cross arm, of an upright, a gusset for fixing said upright to said 15 cross-arm, and a yoke having its ends fixed to said cross-arm on opposite sides of said gusset.

3. In an electric conductor support, the combination with an angle iron cross arm, 20 of an angle iron strut fixed approximately at right angles thereto at its median section, said arm and strut having legs that are approximately parallel and a yoke having its ends fixed to said arm on opposite sides of

said strut, said yoke bowed approximately 25 at right angles to the length of said strut.

4. In an electric conductor support, the combination with a cross arm, of an upright fixed thereto and adapted to lie against a pole in approximately parallel relation thereto, said support having bolt holes therein for fixing it to a pole and permitting the adjustment of the distance between bolts 30 passing therethrough.

5. In an electric conductor support, an iron cross-arm having a vertical leg and a horizontal leg adapted for supporting insulators and fixed to said arm, an angle iron strut having a leg approximately parallel to said vertical leg and a leg approximately 40 parallel to said horizontal leg, said strut having the upper end of one of its legs removed and the upper end of its other leg bent inwardly upon the complementary leg to provide an 45 insulator bearing.

In testimony whereof I have hereunto set my name this 5th day of August, 1921.

HARRY L. HAWKINS.
